UNITED STATES PATENT OFFICE.

LOUIS E. SLAUSON, OF MOLINE, ILLINOIS, ASSIGNOR TO GRID-IRON-GRIP COMPANY, OF ROCK ISLAND, ILLINOIS.

TRACTOR WHEEL.

Application filed January 17, 1919. Serial No. 271,725.

To all whom it may concern:

Be it known that I, LOUIS E. SLAUSON, a citizen of the United States, residing at Moline, in the county of Rock Island and State 5 of Illinois, have invented certain new and useful Improvements in Tractor Wheels, of which the following is a specification.

My invention relates to tractor wheels, of that class which are provided with sectional 10 shoes or tread members, to assist in the support of the wheel when traveling over soft ground. In practice, the soft ground is usually also of a wet and sticky character, so that with many wheels of this class the attachments to the rim soon become filled with the earth, and are rendered more or less inoperative. The principal purpose of the 15 present device is to provide a wheel having a solid rim, and sectional attachments therefor, which rim and attachments will be mutually self-cleaning.

My device is also of a simple and durable construction, and possesses a maximum amount of efficiency.

25 In the drawings:—

Figure 1 is a side elevation of a wheel embodying my invention, with the sectional attachments removed. Fig. 2 is a side view of 30 one of said attachments. Fig. 3 is an end view thereof. Fig. 4 is a side elevation of a complete wheel. Fig. 5 is a longitudinal section on the broken line $x-x$ of Fig. 3.

1 represents the hub of a wheel of usual 35 pattern, 2 the spokes, and 3 the rim thereof. At regular intervals the rim 3 is provided on 40 its outer face with rim elements, preferably in the form of pairs of teeth 4, and on the inner face with bearings 5, which may be secured in place by the same fastening means 45 which hold the teeth 4, as a matter of convenience and economy. Each of the bearings 5 is provided with a pin 6, on the ends 50 of which are supported plates 7, by means of openings 8 of substantially larger diameter 55 than the pin. At their outer edges the plates 7 are formed into treads 9, having outwardly projected teeth 10. These teeth are 60 united by bars 11, (Fig. 5.) which conform outwardly to the shape of the teeth, and have flat inner faces for engagement with 65 the face of the rim 3. The edge of the tread 70 9 is recessed between the teeth 10, as at 12, and the bars 11 are spaced apart, as shown.

In the movement of the wheel the treads 9 are permitted a limited amount of movement with relation to the rim, by reason of the loose connection between the plates 7 and pins 6. As a result, when the shoe is at the bottom of the wheel, and in engagement with the earth, the shoe will be forced upwardly 55 to its farthest inward movement, with the teeth 4 projecting through the recesses 12, and alternating with the teeth 10 and bars 11, forming together one complete shoe or tread. In the continued movement of the 60 wheel, as soon as the shoes are free from the ground they drop away from the rim by force of gravity, and the teeth 4 are practically withdrawn between the treads 9. Any earth which has collected upon the teeth 70 4 is thereby forced off, leaving these teeth clean. When the shoes reach the upper portion of their travel they drop back to the wheel rim and their movement relative to teeth 4 cleans the shoes. The teeth 4 not 75 only assist the wheel in getting a footing in the soft ground, but they also act as plungers, working outwardly through the spaces between the bars 11, and keeping such spaces free from dirt. When the tread members 80 arrive at the lower part of the wheel they again drop outwardly, there being two complete movements thereof inwardly and outwardly in each rotation of the wheel.

As the tread sections approach the ground 85 they hang at such an angle with relation to the rim 3 that they are in a proper position to come in contact with the earth. This is true on either side of the wheel so that it is immaterial in which direction the wheel is moving.

It will be seen that the treads 9 add to the width of the rim to the extent of the thickness of such treads, which thickness may be increased in any reasonable degree. At the 90 time that the greatest pressure is being exerted, when the treads are at the bottom of the wheel, each pair of treads is practically in alignment with the rim.

What I claim and desire to secure, is:

1. The combination with the rim of a wheel, of a bearing on the inner face of said rim, a pin projecting at the sides of said bearing, and a shoe comprising a plurality of transverse ground engaging bars spaced 105 apart, and sides connecting said bars and

plurality of ground engaging elements spaced apart, and sides connecting said elements and having enlarged openings therein 10 engaged by said pin.

In testimony whereof, I affix my signature.

LOUIS E. SLAUSON.

having enlarged openings therein to engage the ends of said pin.

2. The combination of the rim of a traction wheel, of an outwardly extending projection on the rim thereof, a transversely disposed pin on said rim spaced inwardly from said projection, and a shoe comprising a
